ELECTRIC DISPLAY SIGN

Thomas B. McGuire, Rockville, Md., assignor to Reed Research Inc., Washington, D.C., a corporation of Delaware

Application September 17, 1956, Serial No. 610,208

1 Claim. (Cl. 40—52)

The invention relates to electric display signs and more particularly to an electric display sign wherein the illuminated symbols may be changed with facility without resort to complex circuitry.

Electric display signs wherein the illuminated symbols are periodically changed are relatively common. However, such signs normally require complex circuitry and considerable programming in order to achieve the desired degree of versatility and speed. The cost of such circuitry and programming is such that for many applications, signs of this type cannot compete, pricewise, with other display devices.

Accordingly, it is the primary object of the instant invention to provide an electric display sign wherein the illustrated symbols may be changed rapidly with facility and economy.

For a greater appreciation of this and other objects of the invention, reference is made to the following specification and accompanying drawing wherein:

Fig. 1 is a diagrammatic view of an electric display sign constructed in accordance with the instant invention;

Fig. 2 is a top plan view of one of the matrices of the sign illustrated in Fig. 1;

Fig. 3 is a bottom plan view of the matrix of Fig. 2;

Fig. 4 is a view taken along line IV—IV of Fig. 2; and,

Fig. 5 is a view taken along line V—V of Fig. 4.

Referring now more particularly to the drawing, the numeral 1 generally designates an electric display sign having three matrices 2, 3, and 4. It should be understood that although three matrices are indicated herein for illustrative purposes, any number may be employed as desired without departing from the scope of the instant invention.

Each matrix comprises a plurality of neon tubes 5 arranged in rows and columns. As is herein illustrated, there are seven rows and five columns, but it is understood that any number of either may be employed as appears to be best suited for the symbols to be illustrated. As is best seen in Fig. 3, all of the tubes 5 are connected in parallel by means of bus bars 6 and 7. The bus bars 7 are in turn connected in parallel to R.F. oscillator 8 by means of conductors 9 in the manner indicated in Fig. 1. The oscillator 8 may be of any of the suitable types well known in the art, and its exact details form no part of the present invention.

A plurality of laminations 10 composed of non-conductive material and having perforations therein of a size and spacing comparable to the tubes 5 are stacked thereupon as is indicated in Fig. 4. Conductors 11 are interspersed between the laminations and are wrapped about selected ones of the tubes 5 for a purpose and in a manner to be hereinafter described.

As is indicated in Fig. 1, the conductors 11 are all connected to a switching mechanism 12 which is in turn connected to the R.F. oscillator 8 by means of conductor 13. The switching mechanism is adapted to selectively electrically connect the oscillator 8 to desired

2

ones of the conductors 11, and may be manually or automatically actuated. Specific circuitry applicable to the switching mechanism is well known in the art, and requires no further elucidation since the specific details of 5 such circuitry form no part of the instant invention.

When any of the conductors 11 are connected to the oscillator 8, an R.F. voltage will be applied thereto, and an R.F. field will surround the conductors. Such field will be relatively strong in those areas where the conductors are wrapped about the tubes 5 and relatively weak in other areas.

An inherent characteristic of a neon tube is to glow when subjected to an R.F. field of sufficient intensity. Accordingly, those tubes about which the "hot" conductors are wrapped will glow while the remaining tubes will not. By wrapping each conductor 11 about selected tubes 5 as is indicated in Fig. 5, an intelligible glow pattern, in this case the digit "2," can be obtained when an R.F. voltage is applied to the associated conductor 11.

It should be obvious that as many conductors 11 as desired may be employed in conjunction with each tube matrix, and that similarly, as many matrices as desired may be employed in any given display sign. Since each conductor 11 associated with any given matrix is wrapped 20 about a different combination of tubes, the selective application of voltage to the conductors associated with the various matrices will result in the achievement of any desired glow pattern. In Fig. 1 a glow pattern indicating the numeral "293" is illustrated. Shifting the voltage to other conductors would result in a pattern indicative of any other number, word or symbol, dependent solely upon the specific tubes about which the conductors are wrapped.

It may therefore be seen that by merely manipulating 35 the switching mechanism 12 so as to apply voltage selectively to the desired conductors 11, any desired glow pattern may be achieved. Naturally one, or some, or all of the matrices available may be employed at any given time, the number actually used being determined by the

40 number of symbols it is desired to flash simultaneously.

It should be noted that in the illustrative embodiment herein described, neon tubes have been utilized. However, any other means having the characteristic of emitting light when subjected to an R.F. field may be employed in their stead without departing from the scope of this invention:

It may therefore be seen that by utilizing an electric display sign constructed in accordance with the instant invention, the desired number of symbols may be flashed 50 and changed rapidly and with facility.

Having disclosed an exemplary embodiment thereof, what I claim as my invention is:

An electric display sign comprising, a plurality of 55 matrices, a plurality of illuminating means within each matrix, at least some of said illuminating means having the characteristic of emitting light when subjected to an R.F. field, means for generating an R.F. voltage, a plurality of conductors operatively associated with the generating means, each of said conductors being additionally associated with selected ones of the illuminating means within one of said matrices, the selected ones of the illuminating means associated with each conductor being so spaced with respect to one another so as to simulate a specific symbol, and further means interposed 60 between the generating means and the conductors for selectively controlling the application of R.F. voltage to the conductors, the application of R.F. voltage to a conductor resulting in the emission of light by the associated illuminating means so as to form a visual simulation within the corresponding matrix of the related symbol, the concurrent application of voltage to one conductor associated with each matrix thereof resulting in the 65 70

concurrent visual simulation of the related symbols by the illuminating means within the respective matrices.
